GUARD BOLT CONSTRUCTION FOR DOOR LOCKS

George W. Wardwell, Jr., Trumbull, Conn., assignor to Sargent & Company, New Haven, Conn., a corporation of Connecticut

Original application June 28, 1954, Serial No. 439,528, now Patent No. 2,800,347, dated July 23, 1957. Divided and this application January 30, 1957, Serial No. 637,257

3 Claims. (Cl. 292—169)

The invention described in this application, which relates to a door lock and is a division of my application for Door Lock, Serial No. 439,528, filed June 28, 1954, now Patent No. 2,800,347, issued July 23, 1957, is particularly concerned with a guard bolt mechanism for preventing the forcing of the latch bolt by a tool inserted between the door strike and the door.

As illustrated, the structure is applied to a latch bolt mechanism comprising a casing adapted to be inserted in an opening bored into the edge of the door and knob assembly adapted to be applied at each face of the door provided with knob shanks or spindles for actuating the latch bolt. Means are also provided for dogging the latch bolt against operation from the outside of the door as described in my previous application above referred to. In connection with such a structure, it is desirable when the latch bolt is dogged against operation from the outside of the door to provide means for preventing the forcing of the latch bolt into retracted position by a tool inserted between the door and door strike. In the present application means are provided to effect this result in a relatively simple and economical manner and by means of mechanism which occupies a minimum amount of space within the lock case so that the opening in the door in which the case is received may be of relatively small size.

One object of this invention is to provide new and improved guard bolt mechanism for the door lock.

A further object of the invention is to provide means for preventing the forcing of the latch bolt of a door lock by an instrument inserted between the door and door strike, which mechanism will be of relatively simple construction, economical to manufacture, and will occupy a minimum of space within the lock case.

A further object of the invention is to provide guard mechanism for the latch bolt of a door which is controlled by a guard bolt mounted adjacent the latch bolt, and which guard bolt is adapted to cooperate with the door strike to control the position of the guarding or dogging member.

To these and other ends the invention consists in the novel features and combinations of parts to be herein-after described and claimed.

In the accompanying drawings:

Fig. 1 is a front elevational view of a door lock embodying my invention;

Fig. 2 is a horizontal sectional view on line 2—2 of Fig. 1;

Fig. 3 is a vertical sectional view on line 3—3 of Fig. 2;

Fig. 4 is a partial sectional view similar to Fig. 2, showing the guard bolt in a retracted position;

Fig. 5 is a view similar to Fig. 2, showing both latch bolt and guard bolt in retracted position; and

Fig. 6 is a perspective view of the guarding lever.

To illustrate a preferred embodiment of my invention there is shown in Fig. 1 a portion of a door at 10 in

2

which is mounted a door lock mechanism comprising a casing 11 having a face plate 12 through which projects a latch bolt 13 reciprocably mounted in the case.

The latch bolt is provided with a stem 14, which stem projects rearwardly into the case and is provided upon its rear end with lugs 15 adapted to be engaged by the rear face of the web or bight portion 16 of a U-shaped retracting yoke having rearwardly extending legs 17. At its rear end each of the legs 17 of the retracting yoke is provided with a cross head 18 having projecting lugs 19 at each side thereof, which lugs are adapted to be engaged by one or the other of the rollbacks 20.

These rollbacks are carried by hubs 21 rotatably mounted in the rear portion of the casing 11 and adapted to be rotated by spindles 22 connected to the knobs 23 and 24. A dogging member 25 is rotatably and slidably mounted in the casing 11 which is adapted to engage one or the other of the rollbacks 20 so as to dog one of these rollbacks which is operated by the outside knob indicated at 23 in Fig. 1. As the above structure is more specifically shown and described in my parent application referred to above, further description is unnecessary here.

A latch bolt spring 27 bears against the lugs 15 to urge the latch bolt to a projected position. The rear end of this spring bears against a spring stop 28 held by a retaining or abutment member 29 secured to the lock case and extending transversely of the same. A second spring 30 surrounds the first spring and bears against the spring stop 28 at its rear end and at its forward end against the bight portion 16 of the retracting yoke. It will be understood that with this arrangement when the latch bolt is cammed into the case by the closing of the door, only the tension of the spring 27, which is relatively light, must be overcome, but when the bolt is withdrawn by the retracting yoke, both springs must be compressed.

It will also be understood that when either of the knobs 23 and 24 is rotated, one of the rollbacks 20 will also be rotated and, by engaging one of the lugs 19, will effect the retraction of the retracting yoke and will retract the latch bolt into the casing, as shown, for example, in Fig. 5.

The guard mechanism for the latch bolt comprises a guard bolt 32 slidably mounted in the case at the back of the latch bolt, as shown in Figs. 1, 2, 4 and 5. Secured to this guard bolt is a guide plate 33 slidably mounted upon the stem 14 of the latch bolt and, when the guard bolt is in the position shown in Fig. 2, this guide plate is received in a recess 34 at the rear face of the latch bolt. A spring 35 surrounds the stem of the latch bolt between the guide bolt and the bight member 16 of the retracting yoke and normally urges the guard bolt to its protracted position, shown, for example, in Fig. 2.

A guard or dogging lever 36 shown more especially in Fig. 6 is disposed in the case adjacent the guard bolt 32 and extends rearwardly therefrom. The rear end of this member 36 is provided with a hooked portion 37 which extends through an opening in the abutment or retaining member 29 so as to be pivoted thereto to swing inwardly and outwardly toward and away from the latch bolt, as shown in Figs. 2, 4 and 5.

At the forward end of the lever 36 is provided an inwardly extending nose 38 which is adapted in the position shown in Fig. 4 to lie behind a portion of the latch bolt and dog it against retraction. A spring 39 of generally U-shaped form is supported upon the retaining member 29 and the free ends of this spring extend forwardly through openings in this member to urge it inwardly toward its position shown in Fig. 4. The ends of the spring act against a pair of laterally extending arms 40 provided upon the lever 36, these arms, as shown more

especially in Fig. 3, extending out laterally over the legs 17 of the retracting yoke. As shown more especially in Fig. 2, the guard lever 36 is, when the guard bolt 32 is in its protracted position, held outwardly out of position to engage the head 13 of the latch bolt by engagement of the nose 38 with a lug 41 carried by the guide plate 33 which, as previously stated, is secured to the guard bolt.

Each of the legs 17 of the retracting yoke is provided with a cam surface 42 (Figs. 2, 4 and 5) which, when the yoke is retracted, is adapted to engage one of the arms 40 and move the guard lever 36 outwardly from the position shown in Fig. 2 to that shown in Fig. 5. Thereafter during the retracting movement of the yoke, the arms 40 ride upon the edge surfaces 43 of the yoke legs 17 and the nose 38 of the lever 36 is held out of engagement with the latch bolt 13.

As shown in Fig. 2, when the door is open, both guard bolt and latch bolt stand in protracted position and the nose 38 of the guard lever 36 rests upon the lug 41 and is thus held out of the path of the latch bolt. When the door is closed, the latch bolt is cammed inwardly by contact with the strike. As the latch bolt engages the guide plate 33 of the guard bolt, the latter is so carried inwardly with the latch bolt as shown in Fig. 5.

When the door reaches its fully closed position, as shown in Fig. 4, the latch bolt springs outwardly into the opening in the door strike but the guard bolt 32 is held in retracted position by engagement with the strike. In this position of the parts, shown in Fig. 4, the nose 38 of the guard bolt is moved inwardly by the spring 39 so that it lies behind the latch bolt and prevents movement of the latter inwardly by a tool inserted between the door strike and the door. It will be understood at this time the guide plate 33 is in its inward position due to the retraction of the guard bolt 32 so that the lug 41 is no longer in engagement with the nose 38 of the guard lever.

When it is desired to open the door and the retractor is drawn rearwardly by rotation of one or the other of the knobs, the arms 40 on the lever 36 are engaged by the cam surfaces 42 on the legs of the retractor and the guard lever is cammed outwardly against the action of the spring 39 so that the nose 38 no longer stands behind the bolt 13. Upon continued withdrawal of the retracting yoke, the bolt is completely retracted into the case and the door is permitted to open. Upon the opening of the door and release of the knob, both the guard bolt and the latch bolt are moved by their respective springs to their protracted positions shown in Fig. 2.

While I have shown and described one embodiment of my invention, it will be understood that it is not to be limited to all of the details shown, but is capable of modification and variation within the spirit of the invention and within the scope of the appended claims.

What I claim is:

1. In a door lock mechanism having a casing, a latch bolt reciprocably mounted therein, knob-operated means for actuating the bolt including a retracting yoke reciprocably mounted in the casing, guard-bolt mechanism comprising a retaining member fixed to the case rearwardly of the bolt, a guard lever pivoted adjacent its rear end to said member and extending forwardly therefrom, adjacent the wall of the casing, to a point adjacent the bolt and adapted to swing inwardly, in a horizontal direction, at its forward end, said lever having a nose portion at its forward end to engage the bolt and dog it against retraction, a guard bolt reciprocably mounted in the case adjacent the latch bolt, a guide plate secured to the guard bolt and disposed rearwardly of, and embracing the stem of, the latch bolt to be moved rearwardly by the latter upon its retraction, spring means also embracing the latch bolt and acting against said guide plate to urge the guard bolt to a projected position, and means on said guide plate to engage the nose portion of the guard lever when the guard bolt is projected to hold the guard lever in inoperative position.

2. In a door lock mechanism having a casing, a latch bolt reciprocably mounted therein, knob-operated means for actuating the bolt including a retracting yoke reciprocably mounted in the casing, guard-bolt mechanism comprising a retaining member fixed to the case rearwardly of the bolt, a guard lever pivoted adjacent its rear end to said member and extending forwardly therefrom to a point adjacent the bolt and adapted to swing inwardly, in a horizontal direction, at its forward end, said lever having a nose portion at its forward end to engage the bolt and dog it against retraction, a guard bolt reciprocably mounted in the case adjacent the latch bolt, a guide plate secured to the guard bolt and disposed rearwardly of, and embracing the stem of, the latch bolt to be moved rearwardly by the latter upon its retraction, spring means also embracing the latch bolt and acting against said guide plate to urge the guard bolt to a projected position, and means on said guide plate to engage the nose portion of the guard lever when the guard bolt is projected to hold the guard lever in inoperative position.

3. In a door lock mechanism having a casing, a latch bolt reciprocably mounted therein, knob-operated means for actuating the bolt including a retracting yoke reciprocably mounted in the casing, guard-bolt mechanism comprising a retaining member fixed to the case rearwardly of the bolt, a guard lever pivoted adjacent its rear end to said member and extending forwardly therefrom to a point adjacent the bolt and adapted to swing inwardly, in a horizontal direction, at its forward end, said lever having a nose portion at its forward end to engage the bolt and dog it against retraction, a guard bolt reciprocably mounted in the case adjacent the latch bolt, said latch bolt having a rearwardly projecting stem, a guide plate secured to the guard bolt and slidably embracing said stem rearwardly of the latch bolt to be moved rearwardly by the latter when it is retracted, spring means surrounding the latch bolt stem and urging said guide plate forwardly in the casing, and means on said guide plate to engage said lever and hold it in non-dogging position when the guard bolt is in its forward position.
